Minn., assignors to Storm Manufacturing Co.,
Inc., Minneapolis, Minn., a corporation of Min-
nesota

Application December 14, 1933, Serial No. 702,297

9 Claims. (Cl. 77—2)

Our invention relates to a boring machine and more particularly to a boring machine for re-establishing, reborning and refinishing bores in an internal combustion engine cylinder block, of accurate size and alignment.

The object of the invention is the provision of a portable self-contained motor-operated boring machine that is highly efficient and of compact form which permits the same to be mounted on the engine block of an internal combustion engine without removing said block from the chassis of an automotive vehicle and where it is necessary to work close to the cowl or other parts of the vehicle.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary view partly in side elevation and partly in section showing the cylinder block of an internal combustion engine on which the improved boring machine is mounted with its cutter head in one of the bores of said block;

Fig. 2 is a plan view of the feed bar housing head with its cover plate removed to expose the parts housed therein;

Fig. 3 is a fragmentary view principally in section taken on the line 3—3 of Fig. 2;

Fig. 4 is view partly in elevation and partly in section taken on the line 4—4 of Fig. 2;

Fig. 5 is a view principally in section taken on the line 5—5 of Fig. 1;

Fig. 6 is a view principally in section taken on the line 6—6 of Fig. 1;

Fig. 7 is a view partly in side elevation and partly in section taken on the line 7—7 of Fig. 2;

Fig. 8 is a view corresponding to Fig. 7, but on an enlarged scale, in more complete section and further showing additional associated parts;

Fig. 9 is a fragmentary detail view principally in section taken on the line 9—9 of Fig. 8;

Fig. 10 is a view principally in section taken on the line 10—10 of Fig. 8;

Fig. 11 is a view corresponding to Fig. 10 but showing the nut and cage in different positions;

Fig. 12 is a perspective view of the nut operating gear removed from the machine; and

Fig. 13 is a perspective view of the nut removed from its operating gear.

The improved machine, as shown in the drawings, is mounted on the cylinder block of an

internal combustion engine and indicated, as an entirety, by the numeral 14 with the exception of the bores 15.

The improved boring machine includes a cutter head, indicated as an entirety by the numeral 16, with the exception of its radially movable cutting tool 17 and its radially movable centering members 18. This cutter head 16 is rigidly secured to the lower end of a hollow boring spindle or bar 19 in axial alignment therewith and for compound axial and rotary movements through one of the bores 15. Axial movement is imparted to the cutter head 16 by a hollow feed bar 20 through which the boring bar 19 loosely extends in axial alignment therewith. Upper and lower roller bearings 21 and 22 are interposed between the boring bar 19 and feed bar 20 at their upper and lower end portions, respectively, and hold said bars in axial alignment and support the boring bar 19 for rotary movement in said feed bar. The upper roller bearing 21 is held against axial movement on the boring bar 19 between a lower shoulder 23 on said bar and a spur gear 24 keyed to the boring bar 19.

It will be noted that the upper portion of the roller bearing 21 rests on the upper end of the feed bar 20 and the spur gear 24 rests on the roller bearing 21 and overlaps said upper end of the feed bar 20. Obviously the roller bearings 21 and 22 and the spur gear 24 connect the boring bar 19 and the feed bar 20 for common axial movement therewith. The spur gear 24 is held against relative axial movement on the boring bar 19 by the roller bearing 21 and a lock-nut 25 that has screw-threaded engagement with said bar above the spur gear 24.

The feed bar 20 is mounted in a long upright bearing sleeve 26 with freedom for axial sliding movement and which bearing sleeve is integral with a cast base 27. This base 27 is adapted to rest on the flat upper surface of the cylinder block 14 and supports the bearing sleeve 26 with the coincident axes of the boring bar 19, the feed bar 20, and the bearing sleeve 26 perpendicular to the top of said block.

Formed with the base 27 on each side thereof is a hand-piece or lug 28 and above said lug is a hand-hold 29. The top of the base 27 is flat and parallel to the bottom thereof and affords a motor support 30. The bearing sleeve 26 is longitudinally divided at 31 to permit circumferential contraction of said bearing sleeve onto the feed bar 20 to compensate for wear. Formed with the bearing sleeve 26, on each side of its division 31, is an outturned flange 32 and a plu-

rality of draw-screws 33 that connect the two flanges 32 and are operable to contract the bearing sleeve 26 onto the feed bar 20.

The feed bar 20 may be manually operated, 5 to raise or lower the cutter head 16, by a hand-crank 34, normally loose on a short shaft 35, to which is rigidly secured a spur pinion 36 that meshes with a long rack 37 on said feed bar. A simple clutch 38 is provided for temporarily connecting the hand-crank 34 to the shaft 35, at will, and comprises a diametrically extended groove in the outer end of the hub of said crank 10 and a fixed transverse pin in the shaft 35. This clutch pin is arranged to enter the clutch groove 15 by an axial sliding movement of the hub of the hand-crank 34 on the shaft 35. The pinion 36 is mounted in a housing 39, in the form of a boss on the sleeve bearing 26, and the shaft 35 is journaled in said housing. It will be noted that 20 a section of the housing 39, in which one end portion of the shaft 35 is journaled, is removable, as indicated at 40, to afford a passageway for the pinion 36 when placed in the housing 39 or removed therefrom. A set-screw 41 normally holds the housing section 40 in place.

The body of the rack 37 is mounted in a longitudinally extended channel in the feed bar 20 and rigidly secured thereto with its teeth extending with clearance into a longitudinally extended channel 42 in the bearing sleeve 26. The feed bar 20 is held from turning about its axis in the bearing sleeve 26 by a key plug 37' removably mounted in a seat in said bearing sleeve and held in place by a set-screw 39', see Fig. 6.

For the purpose of this case, it will not be necessary to illustrate the mechanism in the cutter head for projecting or retracting the centering members 18, except the rotatable operating rod 43 which extends axially and loosely through 40 the tubular boring bar 19. A hand-piece-equipped wheel 44 for the operating rod 43 is applied to the upper end thereof and has a depending hub 45 turnably mounted on the upper end of the 45 boring bar 19. Neither will it be necessary to show the mechanism for projecting or retracting the cutting tool 17.

The pinion 24 is driven to rotate the boring bar 19, at a single and proper speed for all boring 50 operations, by speed reducing connections from an electric motor 46 mounted on the motor support 30 with its armature shaft 47 parallel to the axis of the boring bar 19. The operating connections from the motor 46 include a relatively small gear 48 keyed to the upper end portion 55 of the armature shaft 47 and meshing with a relatively large gear 49 keyed to the lower end portion of a long vertical shaft 50 journaled in upper and lower bearings in a housing 51 for the 60 gears 48-49. This housing 51 has a cover plate 52 removably held in place by a plurality of screws. Said housing 51 is integral, at one end, with the upper end portion of the bearing sleeve 26 and extends horizontally over the motor 46. 65 The armature shaft 47 is also journaled in bearings in the housing 51 and its cover plate 52. The shaft 50, at its upper end portion, is journaled in bearings in a housing head 53 with freedom for said housing to slide thereon.

Formed with the bottom of the housing head 53, at one end thereof, is a collar 54 which fits on the reduced upper end portion of the boring bar 19, is rigidly secured thereto, and extends 70 horizontally over the housing 51. The housing

head 53 has a cover plate 55 removably held in place by a plurality of screws.

A train of gears in the housing head 53, including the gear 24 which is relatively large, connects the shaft 50 to the boring bar 19 and said train further includes a relatively small gear 56 on the shaft 50 and two intermediate idle gears 57. The gear 56 is free for axial sliding movement on the shaft 50 but is held for common rotation therewith by a key 58 mounted in a longitudinally extended keyway 59 in the shaft 50.

The feed bar 20 is automatically moved axially during the rotation of the boring bar 19 to feed the cutter head 16 to its work, by the following 15 connections actuated by the shaft 50. A worm 60, mounted on the shaft 50 in the housing head 53 above the gear 56, is free to slide axially on said shaft but is held for common rotation therewith by the key 58. Mounted on the shaft 50 20 between the worm 60 and the housing head cover 55 is a roller bearing 60'. Meshing with the worm 60 is a worm gear 61 rigidly secured to one end of a short shaft 62 intermediately journaled in a bearing 63 in the housing head 53. 25 A relatively small beveled gear 64 is rigidly secured to the other end of the shaft 62 and meshes with a relatively large beveled gear 65 loose on a relatively long fixed feed-screw 66 which extends parallel to the axis of the boring bar 19. The lower end portion of the feed-screw 66 is reduced to form a shank 67 mounted in a bore-like seat in a bearing 68 on the bearing sleeve 26. The feed-screw 66 is held against rotation by a shear- 30 ing pin 69, see Fig. 8, which extends diamet- 35 rically through the shank 67 with its end portions anchored in the bearing 68.

The gear 65 is releasably connected to the feed-screw 66 by a novel nut 70 which is longitudinally divided through its center with clearance between the opposing faces of its sections when in mesh with the feed-screw 66. The sections or elements of the nut 70 are mounted between a pair of fixed jaws 71, depending from the hub of the gear 65, and are held thereby for common rotation with said gear but with freedom for movement into or out of mesh with the feed-screw 66. As shown, the curved outer sides of the jaws 71 have the same diameter as the hub on the gear 65 and the inner faces of said jaws are flat and parallel. The opposite sides of the nut 70, which extend between the jaws 71, are also flat and parallel, as indicated at 72, and have a working fit with said jaws which permit the sections of the nut 70 to freely open or close.

A pair of coiled springs 73, mounted in seats in the opposing faces of the sections of the nut 70, are under strain to separate said sections and move the same out of mesh with the feed-screw 66. The nut 70 is mounted in a cylindrical sleeve-like cage 74 turnably mounted in a cylinder seat in the housing head 53. On the lower end of the cage 74 is an axially aligned hub 75 of reduced diameter and which hub is turnably mounted in a seat therefore in the bottom of the housing head 53. A knurled hand-piece 76, by which the cage 74 may be turned about its axis relative to the nut 70, has an annular flange 77 capping the lower end portion of the hub 75 and thereby holds the hand-piece 76 centered relative to the cage 74. The hand-piece 76 is detachably secured to the hub 75 by a plurality of screws. The feed-screw 66 loosely extends axially through aligned holes in the hand-piece 76 and the hub 75. The cage 74 is connected to the gear 65 by a

radially projecting screw-pin 78 anchored to said cage and a circumferentially extended slot 79 in the wall of said cage through which said pin extends. The length of the slot 79 is such as to permit substantially a one-quarter turn of the cage 74 relative to the nut 70.

Formed on the back of each section of the nut 70 is a cam-acting rib or lug 80 that extends longitudinally thereof midway between the two respective surfaces 72. The springs 73 yieldingly hold the sections of the nut 70 at all times with their ribs 80 in bearing contact with the internal surfaces of the cage 74 at diametrically opposite points.

On the internal walls of the cage 74 are diametrically opposite abutment surfaces 81, which are at the smallest diameter of said cage, and when the cam ribs 80 are in engagement with said ribs the nut 70 is in mesh with the feed-screw 66. When the abutment surfaces 81 are under the ribs 80, as shown in Fig. 9, the pin 78 is in contact with the cage 74, at the forward end of the slot 79, and thereby rotate the cage 74 with the gear 65 and the nut 70 which nut is being moved downwardly on the feed-screw 66. This downward movement of the nut 70 on the feed-screw 66 produces the feeding action to the feed bar 20, which lowers the cutter head 16 in one of the bores 15 and thereby feeds the cutting tool 17 to its work.

Midway between the abutment surfaces 81 at diametrically opposite points, the internal walls of the cage 74 are shaped to form nut-releasing surfaces 81' and at which surfaces the cage 74 has its greatest diameter. When the sections of the nut 70 are held by the springs 73 with the ribs 80 on the surfaces 81' the nut 70 is out of mesh with the feed-screw 66. From the cage surfaces 81' the internal walls of the cage 74 are shaped to form cam surfaces 82 that lead to the abutment surfaces 81. When the nut 70 is out of mesh with the feed-screw 66 it is simply rotated by the gear 65 about the axis of said screw.

To release the nut 70 and permit the springs 73 to move the same out of mesh with the feed-screw 66 and thereby stop feeding movement of the feed bar 20, at anytime during boring operation, it is only necessary to grip the hand-piece 76 and turn the cage 74 forward a one-quarter turn relative to the forward turning movement of the nut 70 by the gear 65. The engagement of the cage 74, at the rear end of the slot 79 with the pin 78, limits the forward turning movement of said cage relative to the gear 65 and nut 70 and causes the abutment surfaces 81, followed by the cam surfaces 82, to move from under the ribs 80, which are yieldingly held thereon by the springs 73, and position the cage surfaces 81' back of said ribs. During this movement of the cage 74 relative to the nut 70, said nut has been progressively drawn out of mesh with the feed-screw 66.

To move the sections of the nut 70 into mesh with the feed-screw 66 and thereby start feeding action of the feed bar 20, the hand-piece 76 is gripped and held stationary until the gear 65 has given the nut 70 a one-quarter turn relative to said hand-piece. At the limit of this movement of the nut 70 by the gear 65, the pin 78 will engage the cage 74 at the forward end of the slot 79 and thereby cause the cage 74 to be rotated by the gear 65. While the cage 74 is being held against rotation relative to the rotation of the nut 70 by the gear 65, the ribs 80 have been moved 75 by the cam surfaces 82 onto the abutment sur-

faces 81 and progressively move the nut 70 into mesh with the feed-screw 66.

A pair of drag devices 83 are provided for yieldingly holding the feed bar 20 in the bearing sleeve 26 against downward slipping movement under 5 the action of the weight of said bar. When the nut 70 is out of mesh with the feed-screw 66 the drag devices 83 also hold the feed bar 20 so that the same is positively moved by the pinion 36 and co-operating rack 37 to give an even feed to the 10 feed bar 20 and prevents the said feed bar from intermittently dropping as the teeth of the pinion 36 move out of engagement with the teeth of the rack 37. These drag devices 83 are mounted in radial seats in the bearing sleeve 26 equi-distant 15 on each side of a point diametrically opposite the rack 37 and their outer ends are closed by screw plugs.

Each drag device 83 includes a loose metal shoe held in contact with the periphery of the feed 20 bar 20 by a coiled spring compressed between the respective shoe and screw plug.

For the purpose of this case, it will not be necessary to show the electric circuit for the motor 46, except the movable element 84 of its 25 control switch mounted in a box 85 formed with the housing 51. The switch element 84 may be manually operated to either start or stop the motor 46. To automatically operate the movable switch element to open the switch and stop the 30 motor 46 at the completion of a boring operation, there is provided a longitudinally adjustable trip rod 86 slidably mounted in a bearing lug 87 above said switch element. This bearing lug 87 is formed with the housing head 53 and the trip 35 rod is held where adjusted by a set-screw 88. This trip rod 86 is arranged to engage and operate the switch element 84, at the completion of a boring operation, to open the switch.

In case the feeding action of the feed bar 20 is 40 not stopped either manually or automatically at the completion of a boring operation, the hand-piece 76 will engage the bearing 68 and in case of undue strain on the feed-screw 66, the pin 67 will shear and thereby prevent the machine from 45 being damaged. In case the pin 67 does shear the feed-screw 66 will simply rotate with the nut 70.

For the purpose of this case, it is not thought necessary to show the clamp for securing the 50 boring machine to the block 14.

What we claim is:

1. In a boring machine, a feed bar having a fixed head, and means for operating the feed bar including a fixed screw extending through the 55 head, a driven wheel loose on the screw within the head, a two-part longitudinally divided nut connected to the wheel for common rotation therewith but with freedom for axial sliding movement into or out of mesh with the screw, a cage 60 for the nut rotatably mounted in the head, yielding means holding the sections of the nut in engagement with the cage and out of mesh with the screw, said cage having cam surfaces arranged to engage the sections of the nut when out of 65 mesh with the screw by rotating the cage relative to the nut and move said sections into mesh with the screw, a connection for holding the cage for common rotation with the wheel when the nut is in mesh with the screw, said connection having 70 sufficient play to permit the cage to be rotated relative to the wheel, and a hand-piece on the cage by which it may be held against rotation relative to the wheel or rotated relative thereto.

2. In a boring machine, an upright bearing 75

sleeve, a feed bar mounted in the bearing sleeve for endwise sliding movement, a spindle rotatably mounted within the feed bar, a vertical drive shaft, gearing connecting the vertical drive shaft and spindle and supported on the upper end of the feed bar, means for operating the feed bar from the vertical drive shaft including a screw and a co-operating nut element, one of which is rotated, said nut element being mounted for movement into or out of mesh with the screw, means for moving the nut element into mesh with the screw, and a spring pressed shoe engaging the feed bar for holding the feed bar against downward sliding movement in the bearing sleeve when the nut element is out of mesh with the screw.

3. In a boring machine, a base, an upright bearing sleeve on the base, a tubular feed bar mounted in the bearing sleeve for endwise movement and having a head, a boring bar journaled in the feed bar, an electric motor mounted on the base with its armature shaft parallel to the feed bar, a driven shaft parallel to the boring bar and journaled in said head, driving connections from the armature shaft to the driven shaft, and other driving connections from the driven shaft to the boring bar including an element mounted on the driven shaft for axial sliding movement, a gear driven wheel loosely mounted on said screw, means for operating the feed bar including a fixed screw, a two part nut element on the screw connected to the wheel for common rotation therewith but with freedom for radial sliding movement into or out of mesh with the screw, and cam means surrounding the nut element and connected to the wheel for limited relative turning movement for moving the nut element into and out of mesh with the screw.

4. In a boring machine, a base, an upright bearing sleeve on the base, a tubular feed bar mounted in the bearing sleeve for endwise movement and having a head overlying the base, a boring bar journaled in the feed bar, an electric motor mounted on the base with its armature shaft parallel to the feed bar, a housing on the bearing sleeve between the base and the head, a driven shaft parallel to the boring bar and journaled in bearings in the head and the housing, driving connections in the housing from the armature shaft to the driven shaft, other driving connections on the head from the driven shaft to the boring bar including an element mounted on the driven shaft for axial sliding movement, means for operating the feed bar including a screw fixed to the housing and extending through the head, a gear driven wheel loosely mounted on said screw, a two part nut element on the screw connected to the wheel for common rotation therewith but with freedom for radial sliding movement into or out of mesh with the screw, and cam means surrounding the nut element and connected to the wheel for limited relative turning movement for moving the nut element into and out of mesh with the screw.

5. In a boring machine, a feed bar having a housing head movable with said bar and means for

operating said bar comprising, a fixed screw extending through the head of said bar, a nut element adapted to cooperate with said screw, a driven member embracing said nut element for rotating the same about said screw, a cage in which said nut element and driven member are mounted for limited rotation relative to said cage, and means rotatably mounting said cage in said head and preventing axial movement of said cage, nut element and driving means relative to said head, said cage having cam means arranged to move said nut element into mesh with said fixed screw upon rotation of said cage on its mounting in the head relative to said driven member.

6. The structure defined in claim 5, which further includes a connection from the driven member to the cage for rotating the cage with the driven member when the nut element is in mesh with the screw, said connection having sufficient play to permit a limited movement of the cage, in respect to the driven member and in the same direction of rotation, to move the cam means out of engagement with the nut element and permit the nut element to move out of mesh with the screw.

7. The structure defined in claim 5, which further includes a slot and pin connection between the driven member and the cage for holding the cage for rotation with the driven member when the nut element is in mesh with the screw, said connection permitting a limited turning movement of the cage relative to the driven member and in the same direction of rotation to move the cam means out of engagement with the nut element and permit the nut element to move out of mesh with the screw.

8. In a boring machine, a feed bar having a housing head movable with the bar and means for operating said bar comprising, a fixed screw extending through the head of said bar, a bifurcated driven member loose on the screw, a two-part nut mounted for radial sliding movement between the legs of said driven member for rotation therewith, a cage rotatably mounted in said head and providing a mounting for said driven member and nut, means connecting said cage and driven member against relative axial movement but permitting limited rotation of said cage relative to said driven member and nut, spring means holding the sections of said nut in engagement with said cage, and cam means on said cage arranged to engage the sections of said nut to move same into mesh with the screw upon limited rotation of said cage relative to said driven member.

9. The structure defined in claim 8 which further includes a lost motion connection between the driven member and the cage for holding the cage for rotation with the driven member when the nut is in mesh with the screw, said connection permitting a limited turning movement of the cage relative to the driven member and in the same direction of rotation to move the cam means out of engagement with the sections of the nut and permit the spring means to move said sections out of mesh with the screw.
